Primary Examiner — Robert M Spear*(74) Attorney, Agent, or Firm* — Reinhart Boerner Van Deuren s.c.(57) **CLAIM**

I claim the ornamental design for a dispensing aperture, as shown and described.

DESCRIPTION

FIG. 1 is a front perspective view from above of the claimed design;

FIG. 2 is a back perspective view from above of the claimed design of FIG. 1;

FIG. 3 is a top view of the claimed design of FIG. 1; and,

FIG. 4 is a bottom view of the claimed design of FIG. 1. In the drawings, the broken dot-dash lines define boundaries of the claimed design and form no part thereof. The other broken lines in the drawings depict environmental subject matter only and form no part of the claimed design.
